The ornamental design for a packaging for frozen confection, as shown and described.

DESCRIPTION

FIG. 1 is a front view of a first embodiment of a packaging for frozen confection according to my design;

FIG. 2 is a front view thereof;

FIG. 3 is a cross-sectional view thereof taken along line 3—3 of FIG. 2; and,

FIG. 4 is a cross-sectional view thereof taken along line 4—4 of FIG. 2;

The broken lines represent environmental subject matter and form no part of the claimed design.

The cells or chambers of the various packagings shown herein may typically contain a liquid (which is adapted to be frozen) or a frozen liquid.
